UNITED STATES PATENT OFFICE.

LUTHER E. MORRISON, OF NEW YORK, N. Y., ASSIGNEE TO MERGENTHALER LINOTYPE COMPANY, A CORPORATION OF NEW YORK.

TYPOGRAPHICAL DISTRIBUTING MACHINE.

Application filed February 11, 1925. Serial No. 3,363.

To all whom it may concern:

Be it known that I, LUTHER E. MORRISON, a citizen of the United States, residing at New York, in the county of New York, 5 State of New York, have invented certain new and useful Improvements in Typographical Distributing Machines, of which the following is a specification.

This invention relates to typographical machines, such as linotype machines of the general organization represented in U. S. Letters Patent to O. Mergenthaler, No. 436,532, wherein circulating matrices are released from a magazine in the order in which 10 their characters are to appear in print and then assembled in line, the composed line transferred to the face of a mold, the mold filled with molten metal to form a slug or linotype against the matrices which produce 15 the type characters thereon; and the matrices thereafter returned through a distributing mechanism to the magazine from 20 which they started. In some machines, such as the commercial model 9, where matrices 25 may be drawn from several magazines and mixed together in the same line, the distributing mechanism includes a primary distributor which first sorts the matrices according to font, and a plurality of main dis- 30 tributors which thereafter sort the matrices of the individual fonts according to character and restore them to their proper channels in the magazines. With this type of 35 distributing mechanism, the matrices, after font separation, pass down chutes or tubes and enter so-called lower distributor boxes, 40 wherein they are guided upon inclined rails into engagement with reciprocating pawls or escapements, which feed them one at a 45 time to the main distributors. In order that these pawls or escapements may cooperate properly with the matrices, the latter are provided in their bottom edges with central notches, which necessarily vary in shape and 50 depth according to the thickness of the individual matrices. Besides adding to the cost of production, such notches in the matrices necessarily limit the space ordinarily required for the regular font notches and, 55 moreover, seriously weaken the matrices, especially when the latter are formed with other necessary cuts or notches. Further-

more, matrices comprising fonts used on other machines, such as those of the single distributor class, are excluded from use on 55 machines of the multiple distributor class described, since they do not have the required central notches.

Primarily, the present invention is intended to obviate the foregoing difficulties and 60 contemplates certain improvements whereby the distributing mechanism may receive and handle matrices of all fonts whether they have or have not the objectionable central notches referred to. To this end, each of the 65 lower distributor boxes is provided with shoulders arranged to engage the matrices by their projecting ears and arrest them in the path of a vertically reciprocating finger, which lifts them successively above the 70 shoulders so that they may escape, one at a time, into position to be picked up by the distributor screws. In the embodiment illustrated, the matrix arresting shoulders are 75 formed on horizontally reciprocating sections of the box guide rails, which latter are also formed with inclined guiding surfaces leading downwardly from the shoulders to the pick-up position of the screws. In the operation of the parts, as each matrix 80 is raised by the lifting finger, the rail sections are shifted rearwardly or retracted to bring the inclined surfaces beneath the upper projecting ears of the lifted matrix, which then, as the lifting finger recedes, 85 slides down the inclined surfaces into direct engagement with the distributor screws. The screws are preferably recessed or cut away at points adjacent their receiving ends to present suitable banking surfaces to the 90 matrices as they enter the threads.

In the accompanying drawings, the invention has been shown merely in preferred form and by way of example and as applied to the specific type of distributing 95 mechanism indicated. However, many changes and variations may be made therein and in its mode of application, which will still be comprised within its spirit. It is to be understood, therefore, that the invention is not limited to any specific form or embodiment, 100 except in so far as such limitations are specified in the claims.

In the drawings:

Fig. 1 is a side elevation, partly broken away, of the improved distributor box;

Fig. 2 is a vertical transverse section, taken on line 2—2 of Fig. 1;

Fig. 3 is an elevation, similar to a portion of Fig. 1, showing the parts in a different position; and

Fig. 4 is a detail plan view, showing the connections between the rail sections and the actuating cam.

The matrices X are released by the primary distributor (not shown) and dropped into the tubes or chutes A, arranged in communication with the lower distributor boxes B, through which they are guided and sustained in upright position by the engagement of their projecting ears X¹ with the upper and lower inclined rails B¹ B². Each distributor box is associated with a main distributor, which comprises, as usual, the longitudinally ribbed or permuted bar C and the set of matrix conveying screws C¹, the latter being arranged to pick up matrices as they emerge from the box and advance them across the horizontal rail extensions B³ B⁴ into engagement with the bar C and thence along the same until finally released above their proper magazine channels. The foregoing parts and their mode of operation, except as hereinafter pointed out, are or may be of any approved construction or as embodied in the commercial model 9 linotype.

According to the present invention, each of the distributor boxes B is provided with upper and lower pairs of shoulders B⁵ B⁶, arranged to arrest a gravitating matrix by its projecting ears before it reaches the pick-up position of the conveying screws. The shoulders B⁶ of the lower pair are fixed, being formed on the lower guide rails B², while, for reasons which will presently appear, the shoulders B⁵ of the upper pair are formed on horizontally reciprocating sections B⁷ of the upper guide rails B¹. These rail sections B⁷ are also formed with short inclined surfaces B⁸ leading downwardly from the shoulders B⁵ and adapted to guide the escaping matrices into position to be picked up by the leading ends C² of the conveying screws. A yoke member B⁹, slidably mounted in the box casing (see Figs. 1 and 4), supports the rail sections B⁷ and is actuated back and forth by a grooved cam C³ secured to one of the constantly rotating screws C¹. A stud B¹⁰ protruding from the cross-piece B¹¹ of the yoke member and having a pin B¹² arranged to engage in the groove C⁴ of said cam serves as the necessary operating connection. The release of the arrested matrices is effected by the employment of the ordinary lifting finger D, pivotally connected to the free end of a yielding lever D¹ and guided in its vertical

movements by a transverse pin B¹³ against which it is held under the tension of a light helical spring B¹⁴. The lever D¹ is pivoted at D² and is operated from one of the screws C¹, through an adjustable link D² connected to a pin D⁴ eccentrically fastened into the face of the grooved cam C³.

From the foregoing arrangement, it will be seen that after an arrested matrix is raised above the shoulders B⁵ B⁶ by the lifting finger D, the rail sections B⁷ are moved rearwardly by the cam C³ to bring the inclined surfaces B⁸ beneath the upper projecting ears of said matrix (see Fig. 3), which then, as the lifting finger recedes, slides down the inclined surfaces and reaches pick-up position in time to be engaged by the leading ends C² of the screw threads. In this connection, it may be noted that the cam groove C⁴ is concentrically formed in two planes to cause the rail sections B⁷ to dwell in both their fore and aft positions, thus allowing ample time for a matrix first to be lifted above the arresting shoulders and then to escape down the inclined surfaces B⁸ to the screw pick-up position.

The matrix conveying screws C¹ are preferably of the general type shown in the Guest application, Serial No. 655,166; that is to say, the following side faces of the screw-threads, as distinguished from the leading side faces thereof, and at points adjacent their receiving ends, are cut away or recessed to present vertical circumferential surfaces C⁵ extending about half-way around the first convolution. These surfaces C⁵ afford desirable banking surfaces for the matrices, and, as a matter of fact, constitute stops which, under normal conditions, are presented to the projecting ears of the matrices as they escape, one after another, from the box. The matrices are thus squarely arrested in the pick-up zone, but inasmuch as they might have a tendency to recoil or rebound because of their impact with said banking surfaces and stop the distributor, the fixed lower guide rails B² and the retractile rail sections B⁷ are respectively provided with shoulders or abutments B¹⁵ and B¹⁶, which serve to restrain the matrices against abnormal rearward displacement when they reach the pick-up position. It will be noted that when the rail sections B⁷ are drawn beneath the projecting ears of a lifted matrix, the shoulders B¹⁶ are disposed in the same vertical plane as the shoulders B¹⁵. Ample room and time are thus afforded an escaping matrix to reach the pick-up position before being carried away by the screws.

It is also proposed, in the present construction, to provide the box with an ordinary separator blade E, which serves to prevent more than one matrix being lifted at a

time by the finger D. The blade E functions substantially the same as heretofore, being spaced from the arresting shoulders horizontally a distance slightly greater than the thickness of the thinnest matrix, and being arranged to cooperate with the usual central cuts X² with which the thicker matrices are provided. Thus, a leading matrix arrested by the shoulders B⁵ B⁶ (as shown in Fig. 1) may be lifted by the finger D, but a succeeding matrix will be held down by the blade E.

While, in the present embodiment, the inclined surfaces which direct the matrices to the screw pick-up position are formed on sections forming part of the box guide rails, this is not absolutely essential, as the surfaces could be formed on other parts independent of the box rails. Nor is it essential that the matrix arresting shoulders be formed on the same parts that have the inclined surfaces. The arrangement illustrated, however, is very simple and is preferred.

Having thus described my invention, its construction and mode of operation, what I claim and desire to secure by Letters Patent of the United States is as follows:

1. In a typographical distributing mechanism comprising a distributor bar and set of matrix conveying screws, the combination of guide means along which the matrices pass by gravity, means for arresting the gravitating matrices at a point in advance of the conveying screws, means for releasing the arrested matrices, one at a time, to permit their escape into position to be picked up by the screws, and inclined surfaces movable into engaging relation to the released matrices for directing them to the pick-up position.

2. In a typographical distributing mechanism comprising a distributor bar and set of matrix conveying screws, the combination of guide means along which the matrices pass by gravity, shoulders for arresting the gravitating matrices at a point in advance of the conveying screws, a reciprocating finger for lifting the matrices successively above the shoulders, and inclined surfaces movable beneath the projecting ears of the lifted matrices for directing them into position to be picked up by the screws.

3. In a typographical distributing mechanism comprising a distributor bar and a set of matrix conveying screws, the combination of guide means along which the matrices pass by gravity, shoulders for arresting the gravitating matrices at a point in advance of the conveying screws, means for lifting the matrices successively above the shoulders, and means for retracting said shoulders to permit the escape of the lifted matrices into position to be picked up by the conveying screws.

4. In a typographical distributing mechanism comprising a distributor bar and a set of matrix conveying screws, the combination of guide means along which the matrices pass by gravity, a reciprocating matrix lifting finger, means for arresting the gravitating matrices in the path of the finger, inclined surfaces for guiding the matrices into position to be picked up by the conveying screws, and means for moving said surfaces beneath the projecting ears of the lifted matrices so as to direct them to the pick-up position.

5. In a typographical distributing mechanism comprising a distributor bar and a set of matrix conveying screws, the combination of a distributor box, guide rails arranged therein and having movable sections formed with shoulders against which the matrices are arrested, a reciprocating finger for lifting the arrested matrices successively above said shoulders, and means for retracting the rail sections to permit the escape of the lifted matrices into position to be picked up by the conveying screws.

6. In a typographical distributing mechanism comprising a distributor bar and a set of matrix conveying screws, the combination of a distributor box, guide rails arranged therein and having movable sections formed with shoulders against which the matrices are arrested and formed further with inclined surfaces leading downwardly from said shoulders, a reciprocating finger for lifting the arrested matrices successively above the shoulders, and means for retracting the rail sections to bring the inclined surfaces beneath the projecting ears of the lifted matrices, for the purpose described.

7. In a typographical distributing mechanism comprising a distributor bar and a set of matrix conveying screws, the combination of a distributor box, upper and lower guide rails arranged therein, matrix arresting shoulders formed on the lower rails, movable sections forming part of the upper rails and having arresting shoulders corresponding to those of the lower rails, a reciprocating finger for lifting the arrested matrices successively above said shoulders, and means for retracting the movable rail sections to permit the escape of the lifted matrices into position to be picked up by the conveying screws.

8. In a typographical distributing mechanism comprising a distributor bar and a set of matrix conveying screws, the combination of a distributor box, upper and lower guide rails arranged therein, the upper rails having horizontally reciprocating sections formed with matrix arresting shoulders and with inclined surfaces leading downwardly from said shoulders, a reciprocating finger for lifting the arrested mat-

rices successively above the shoulders, and means for operating the lifting finger and the movable rail sections in proper synchronism, so as to effect the release of the arrested matrices and permit their escape, one at a time, down said inclined surfaces into position to be picked up by the conveying screws.

9. In a typographical distributing mechanism comprising a distributor bar and a set of matrix conveying screws, the combination of guide means along which matrices pass by gravity, means for arresting the matrices at a point in advance of the conveying screws, means for releasing the arrested matrices, one at a time, and movable inclined surfaces down which the released matrices escape into position to be picked up by the screws, the said screws at their receiving ends being recessed or cut away so as to present vertical circumferential banking surfaces to the escaping matrices.

10. In a typographical distributing mechanism comprising a distributor bar and a set of matrix conveying screws, the combination of a distributor box, guide rails arranged therein and having movable sec-

tions formed with matrix arresting shoulders and with inclined surfaces leading downwardly from said shoulders, a matrix lifting finger, and means for operating the lifting finger and the movable rail sections in feeding the matrices to the conveying screws, the said screws being formed with vertical circumferential matrix banking surfaces, and the rail sections presenting shoulders to restrain the matrices against rearward displacement when they are arrested by the screw banking surfaces.

11. In a typographical distributing mechanism comprising a distributor bar and a set of matrix conveying screws, the combination of a distributor box, shoulders for arresting the matrices within the box, a reciprocating finger for lifting the arrested matrices successively above the shoulders, a separator blade to prevent more than one matrix being lifted at a time, and means for displacing the arresting shoulders to permit the escape of the lifted matrices into position to be picked up by the conveying screws.

In testimony whereof, I have affixed my signature hereto.

LUTHER E. MORRISON.
